Geo. W. Heiland, INVENTOR,

BY HIS ATTORNEY Lewis J. Doolittle.

UNITED STATES PATENT OFFICE.

GEORGE W. HEILAND, OF NEW YORK, N. Y.

SMOKE-MACHINE.

No. 821,489.

Specification of Letters Patent.

Patented May 22, 1906.

Application filed April 10, 1905. Serial No. 254,725.

To all whom it may concern:

Be it known that I, GEORGE W. HEILAND, a citizen of the United States, and a resident of New York, in the county of New York and State of New York, have invented certain new and useful Improvements in Smoke-Machines, of which the following is a specification.

This invention relates to a device for the testing of plumbing or a system of pipes by means of what is known as a "smoke test" for the purpose of detecting and locating any leaks in the same.

Smoke is very penetrating and will, when forced into pipes under a small pressure, issue from any opening therein, however small, enabling a leak to be easily located.

Another method frequently used is to force air into the pipes, having first allowed the air to pass over a solution of peppermint, thus enabling a leak to be located by the odor of the escaping gas.

The object of my invention is to provide a simple and efficient device for applying either of these tests. The device consists in an outer inclosing case, preferably in the form of a vertical cylinder, supported on suitable standards and containing an inner tank or reservoir, also circular in form and having a double wall with a space between partially filled with water. A floating cover is provided which closes the above-described reservoir and provides a space from which the generated smoke is led to the pipes to be tested. If there be any leaks in the pipes which will allow the smoke to escape, this cover will slowly settle, and thus indicate such a leak.

A separate and removable fire-box for the generation of the smoke is designed to fit the space on the inside of the inner reservoir-wall. This fire-box is of peculiar construction and contains an adjustable attachment for holding a specially-prepared fuel which will generate a dense smoke, as will be more fully explained hereinafter.

A further feature of my device is in the method of taking the smoke from the device to the pipes to be tested. An offset trap-fitting is provided through which the smoke must pass and which on account of its construction will cause any water-vapors to be condensed therein and allow only the dry smoke to pass through to the pipes. A valve is provided at the bottom of this fitting to allow any accumulated water to be drawn off and also to indicate the color and density

of the smoke passing therethrough. This offset fitting may also be used as a reservoir to contain a peppermint solution when it is desired to use the machine for this kind of test.

To generate smoke in the machine, a blower may be used which is so constructed as to provide a continuous draft of air at a uniform pressure. This has been found by numerous experiments to give the best results and provides for a continuous flow of smoke of uniform density.

The operation of this machine will be clearly understood and more fully explained in connection with the accompanying drawings.

Figure 1 represents a side elevation of a device embodying my invention as used in connection with a blower of the type described. A portion of the cylinders surrounding the smoke-chamber and fire-box is broken away to show more clearly the interior construction. Fig. 2 is a cross-sectional view of a portion of the specially-prepared fuel-blocks enlarged. Fig. 3 is a top plan view and section of the removable fire-box, showing the fuel-block in place. Fig. 4 is an enlarged sectional view of a portion of Fig. 3. Fig. 5 is an enlarged sectional view of the blower shown in Fig. 1.

At 1 is shown a vertical cylindrical outer jacket which may be constructed of wooden strips held in place by circular band 2 and supported upon suitable standards, such as 3.

A tank or reservoir having an outer wall 4 and inner wall 5 is provided with a space between said walls which is partially filled with water and in which a floating cover 6 acts as a gage to determine if any smoke escape from leaks in the pipes, allowing the cover 6 to settle, as has been stated. A fire-box 7 is arranged to fit in the space inside of the wall 5 of the water-reservoir. This fire-box is perforated, as shown, and is provided with a grate at the bottom thereof. Suitable standards, such as 8, are provided to support the same at a sufficient distance from the base of the device to allow the air-draft to be introduced underneath the grate through a supply-pipe 9. A blower 10 is connected to the supply-pipe, and the flow of air therein is controlled by a shut-off valve 11. This blower is so constructed that a continuous flow of air at a uniform pressure is supplied to the fire-box.

The construction of the blower (shown at

10 in Fig. 1) is shown in the sectional view in Fig. 5. This blower is provided with a driving-shaft 30, which may be turned by hand or other suitable means. Mounted upon and secured to the shaft 30 is a large gear 31, which meshes with a small gear 32, which is mounted upon and secured to a shaft 33. This shaft also carries a gear 34, which meshes with and drives a worm 35, secured to the vertical shaft 36. At the lower end of the worm-shaft 36 are provided fan-blades, such as 40, which are secured to this shaft by the hub 37. This fan is inclosed in a suitable housing 38 and provided with an outlet at 39, from which the air is taken by suitable connecting-pipes to the interior of the smoke-machine, as shown in Fig. 1. It is thus seen that the rotary motion of the driving-shaft 30 of the blower is multiplied many times by means of the series of driving-gears and that consequently a very rapid rotation of the fan-blade 40 may be produced and the flow of air from the blower to the smoke-machine will be continuous and at a uniform pressure, which has been found to give much better results and to provide a more efficient test than any other means.

The advantages of a continuous flow of air at a uniform pressure, resulting in a continuous flow of smoke of a constant and a uniform density from the smoke-machine, will be evident.

The fire-box is separate from the rest of the device and may be easily removed therefrom for the purpose of cleaning or repairing. On account of its peculiar construction and the perforated walls, which allow the air-draft to be forced through and out of the box at all points, it has been found that a large volume of smoke is easily and quickly generated. This smoke is collected in the space in the interior of the floating cover 6, from whence it is taken through a vertical pipe 12 to the offset fitting 13, which is provided with a suitable means for attachment to the pipes to be tested.

On account of the trap formed by the offset in this fitting 13 any water-vapors which may be carried out from the smoke-chamber will be condensed therein and not carried to the pipes under test. These may be drawn off from the trap by means of the valve 14.

A valve 15, which may be designated as the "peppermint-valve," may be located at the upper end of this fitting to provide for the pouring in of a peppermint solution. The air now passing over this solution in the bottom of the trap 13 will collect the vapors therefrom and carry the same to the pipes under test. It is thus seen that this trap serves a twofold purpose.

A fuel-block, which is designed to fit the interior of the fire-box 7, is composed of successive layers of tin, tar-paper, cotton, paste-board, and burlap, formed in the shape

shown in Fig. 3. The outer layer 16 is of corrugated tin, layer 17 is of tar-paper, layer 18 of cotton, and layer 19 of pasteboard, also corrugated, layer 20 of burlap, and layer 21 of tar-paper. This block when formed into the shape as shown is dipped for approximately half its thickness from the bottom up into pitch or other inflammable material. The upper half is then dipped into crude oil, so forming a combination which will generate a dense smoke when ignited.

The interior surface of the fire-box is provided with a slide 22, which engages a corresponding projection 23 on the fuel-block, thus enabling the same to be easily placed and held in position in the fire-box.

An offset 24 in the wall of the fire-box 7 is provided to allow the outlet-pipe 12 to be brought to the upper portion of the smoke-chamber.

The construction of the water-reservoir 5 provides a continuous water-jacket around the fire-box, as well as providing a water seal with the floating cover 6.

The device, as shown in combination with the blower, as described, is intended as an illustration of one embodiment of my invention, and it will be evident that many changes may be made in detail of construction without departing from the scope thereof.

What I claim is—

1. A smoke-machine having a water-jacket inclosing a fire-box, a fire-box provided with a grate and open at the top and also having openings in the side thereof, and means for maintaining a continuous flow of air at a constant pressure through said fire-box to produce a continuous flow of smoke at a constant pressure from said machine.

2. A smoke-machine having a water-jacket inclosing a fire-box, a removable fire-box provided with a grate and open at the top and also having openings in the sides thereof, and means for maintaining a continuous flow of air at a constant pressure through said fire-box to produce a continuous flow of smoke at a constant pressure from said machine.

3. In a smoke-machine, the combination of a removable perforated fire-box, a water-reservoir surrounding said fire-box, a cylindrical float closed at its upper end and having the lower portion thereof immersed in the water in said reservoir, an outlet-pipe leading from the interior of said float to a connection for communicating with the pipes to be tested, and means for maintaining a continuous flow of air through said fire-box, substantially as described.

4. In a smoke-machine, the combination of a removable fire-box, a water-reservoir surrounding said fire-box, a cylindrical float closed at its upper end forming a smoke-chamber therein and having the lower portion thereof immersed in the water in said

reservoir, an outlet-pipe leading from said smoke-chamber to a U-shaped connection at the lower part of said smoke-machine, said U-shaped connection forming a trap in which any water-vapors will be condensed and collected, an outlet and connection from said trap to the pipes to be tested, substantially as described.

5. In a device for the discovery of leaks in pipes, the combination of a reservoir having an inner and outer wall, a float closed at its upper end and having the lower portion thereof immersed in the water in said reservoir thus forming a chamber of variable size 15 on the interior of said float and reservoir, means for supplying air in a continuous flow at a constant pressure to said chamber, an outlet-pipe leading from said chamber to a U-shaped connection at the lower part of said device, a U-shaped connection adapted to contain a peppermint solution in the lower portion thereof, and an outlet forming a connection to the pipes to be tested, substantially as described.

25. 6. In a smoke-machine, the combination of a removable perforated fire-box, a water-reservoir surrounding said fire-box, a float closed at its upper end and having the lower portion thereof immersed in the water of said reservoir, an outlet-pipe leading from the interior of said float to a connection to the pipes to be tested, a blower having a rotary blade driven by means of a worm and gear 65 substantially as described.

30. 7. In a smoke-machine, the combination of a removable perforated fire-box, a water-reservoir surrounding said fire-box, a float closed at its upper end and having the lower portion thereof immersed in the water of said reservoir, an outlet-pipe leading from the in-

terior of said float to a connection to the pipes to be tested, a blower having a plurality of rotary blades and adapted to maintain a continuous flow of air through said fire-box, 45 substantially as described.

8. In a smoke-machine, the combination of a removable perforated fire-box, a water-reservoir surrounding said fire-box, a float closed at its upper end and having the lower 50 portion thereof immersed in the water of said reservoir, an outlet-pipe leading from the interior of said float to a connection to the pipes to be tested, a blower having a rotary blade driven by means of a worm and gear 55 and adapted to maintain a continuous flow of air through said fire-box, substantially as described.

9. In a smoke-machine, the combination of a removable perforated fire-box, a water- 60 reservoir surrounding said fire-box, a float closed at its upper end and having the lower portion thereof immersed in the water of said reservoir, an outlet-pipe leading from the interior of said float to a connection to the 65 pipes to be tested, a blower having a rotary blade driven by means of a series of gears and adapted to maintain a continuous flow of air through said fire-box, substantially as described.

10. A smoke-machine having a fire-box 70 provided with a slide adapted to engage a fuel-block and retain the same in position in said fire-box.

Signed at New York, in the county of New 75 York and State of New York, this 4th day of April, A. D. 1905.
